UNITED STATES PATENT OFFICE

102,974

DESIGN FOR A COMBINED SUN VISOR AND VENTILATOR FOR MOTOR VE- HICLE WINDOWS

Nelle W. Pritchard, Atlantic Beach, Fla.

Application November 2, 1936, Serial No. 65,648

Term of patent 14 years

To all whom it may concern:

Be it known that I, Nelle W. Pritchard, a citizen of the United States, residing at Atlantic Beach, in the county of Duval and State of Florida, have invented a new, original, and ornamental Design for a Combined Sun Visor and Ventilator for Motor Vehicle Windows, of which the following is a specification, reference being had to the accompanying drawing, forming part thereof.

Figure 1 is a perspective view of a combined sun visor and ventilator for motor vehicle windows, showing my new design.

Fig. 2 is a front elevation thereof.

Fig. 3 is a sectional view taken on the line 3—3 of Fig. 2.

The design is characterized by having one end bent in a substantially right angle while the other end tapers to a substantially scimitar tipped form.

I claim:

The ornamental design for a combined sun visor and ventilator for motor vehicle windows substantially as shown and described.

NELLE W. PRITCHARD.
